UNITED STATES PATENT OFFICE.

HARRY RANDOLPH VAN DEVENTER, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY.

MANUAL TRIPPING MECHANISM FOR IGNITERS.

1,245,830.

Specification of Letters Patent.

Patented Nov. 6, 1917.

Application filed December 24, 1914. Serial No. 878,932.

To all whom it may concern:

Be it known that I, HARRY RANDOLPH VAN DEVENTER, a citizen of the United States, residing at Sumter, in the county of 5 Sumter and State of South Carolina, have invented certain new and useful Improvements in Manual Tripping Mechanism for Igniters, of which the following is a specification, reference being had to the accompanying drawing.

My invention relates to ignition apparatus for internal combustion engines, and has for its object the production of a self-contained ignition unit, which may be operated 15 either by the engine to which it is attached or by hand, which shall be compact, highly efficient, and require a minimum number of parts. In order to attain my object, I assemble and mount the operating parts of the 20 unit on a bracket which is preferably attached to and integral with the body of the igniter. In the preferred form of the device, this bracket carries the actuator or trip lever, the operating means for the movable 25 electrode of the igniter, the necessary springs and connecting means, the detachable magneto, and the hand firing lever. According to one modification, the hand firing lever is mounted upon the engine cylinder or 30 to a separate part connected thereto, independently of the main supporting bracket. The characteristic feature of my invention is that the operating parts are assembled together on the bracket, without being dependent upon the magneto machine or its 35 frame. This independence enables the magneto to be detachable, and of any standard design which is an important factor in manufacture and makes for greater efficiency 40 as well as economy. This also enables hand firing to be accomplished without the magneto. As will appear from the detailed description, this hand firing covers both the magneto and the igniter (using battery to 45 furnish current for the latter when the magneto has been removed); and I am not aware of any device in the prior art having this flexibility, or indeed making it possible to hand fire without a magneto, and without 50 altering the general operation of the engine and ignition system. In this respect, as well as in others which will presently appear, the present design is an improvement over those heretofore proposed and patented by others.

As my present invention constitutes the 55 first solution known to me of the problem of applying a hand firing lever without depending upon a special magneto machine, or a magneto machine having a special frame work, I shall claim broadly herein the combination presented, of the actuating parts with a hand firing device mounted and supported independently of the magneto machine as such.

My invention is illustrated in the accompanying drawings in which—

Figure 1 is a plan view of my ignition unit applied to a cylinder wall, shown in section.

Fig. 2 is a front elevation of the same.

Fig. 3 is a front elevation of a modification in which the hand firing lever is supported directly upon the cylinder of the engine.

In the drawings, 1 indicates a wall of 75 the engine cylinder, which may be of any standard or desired type to which this general type of ignition apparatus is applicable. 2 indicates the body of an igniter which enters the cylinder through an opening in the wall 1. 3 indicates the movable electrode of the igniter coöperating with a fixed electrode 4 carried on the body. The electrode 3 is mounted on a shaft 5 which extends through the body 2, for operation 80 by mechanism external to the cylinder. Secured to the body 2 is a bracket 7 projecting from the engine cylinder in a plane parallel to the axis of the igniter, and preferably horizontal. Integral with this bracket, 85 and also with the igniter body 2, is a plate or flange 6 carrying arms 8 and 9 upon which are mounted posts or studs 10 and 11, serving as fixed anchorages for the outer ends of the operating springs 12 and 13. 90 Mounted upon the igniter shaft 5, and adapted to oscillate freely thereon, being detachably connected to 32 of the magneto, is an actuator or trip lever 14 with an upwardly projecting finger 15 in the path of 95 reciprocating travel of a push rod 16 which when the engine is running is moved back and forth as indicated by the double headed arrow in Fig. 2. This reciprocating motion may be imparted to the push rod by a 100 crank or cam or other device driven by the engine in a manner which will be well understood by those skilled in the art. The 105

engagement of the parts 15 and 16 is adapted to be controlled by two other independent elements, the first being an eccentric 17 mounted on a fixed shaft 18 and rotatable by 5 means of a handle 19; and the second element being the bell crank lever 20—21, whose arm 20 lifts the push rod 16 so that it cannot engage the finger 15, when the arm 21 is forced to the left as indicated in dotted lines in Fig. 2, by a pin or stud 22 on the exhaust valve operating rod 23. The function of the eccentric cam 17 is to effect timing of the spark by determining the extent of engagement of the end of the push 10 rod 16 with the finger 15, and thereby the exact point in the stroke of the push rod at which it will slip over the point of the finger 15 and permit the actuator to be snapped back by the springs. The function of the bell crank lever 20—21 is to disengage the push rod entirely and prevent actuation of the trip lever 14 on the exhaust stroke. This of course is particularly applicable to 15 a "hit-and-miss" engine.

25 The electrodes 3 and 4 are normally maintained in engagement by means of a helical spring 24 (see Fig. 1) having one end attached to the flange or frame 6 and the other end attached to the electrode shaft 5.

30 The opening of the electrodes is accomplished by means of a dog 25 rigidly fixed on the electrode shaft and carrying a screw tappet 26, engaged from beneath by a stud 27 carried on the actuator or trip lever 14.

35 This stud serves also for the attachment of the spring 12, each end of the actuator being slotted to receive the eye on the end of the spring. The outer end of the stud 27 also projects through and beyond the actuator, far enough to be engaged by the end 40 of the hand firing lever 29 which is in the form of a bell crank having an upwardly projecting handle 30 and mounted at its angle on the outer end of the post or stud 45 10. A pin 28 at the opposite end of the actuator 14 from the stud 27 receives and holds the eye on the end of the spring 13, and the parts are so proportioned that when the actuator is in the position shown in 50 Fig. 2, that is to say in the normal non-firing position, its axis will approximately coincide with the axes of the spring helices, the springs being under sufficient tension to maintain this position.

55 Outside of the actuator, a magneto machine 31 is mounted on the bracket 7, this machine being shown in plan in Fig. 1, but being removed in Fig. 2 and the bracket shown in section, in order to expose the 60 operating parts. This magneto, as already stated, may be of any stated type or structure provided it has a rotor or oscillator capable of producing a spark as required by the igniter. I do not herein claim any 65 specific means for attaching the rotor or

oscillator of this magneto to the other parts, and particularly to the actuator, but I have indicated a connection at 32 in Fig. 1 between the shaft of the magneto and the actuator 14, which it will be remembered is 70 free to oscillate on the shaft 5 of the movable electrode 3. The connection thus indicated may be by means of screws, or a combination collar, or any desired type of coupling or connection, many devices suitable 75 for this purpose being well known in the art, and one of them, a detachable pin and slot crank coupling being described and illustrated in my prior application Serial No. 878,196, filed December 19, 1914. 80

The operation of my unit thus described is as follows:

Assuming the parts to be in the position shown in Fig. 2 and that the engine has been turned into the proper position by 85 hand, with suitable compression in the cylinder, the hand firing lever 30 is moved to the right (Fig. 2), which swings the lever arm 29 about its center post 10, so that the bearing face of the lever 29 will engage 90 the end of the stud 27 and force down the corresponding end of the trip lever 14, so as to oscillate the latter on its shaft and place both springs 12 and 13 under tension. The bearing face of the lever 29 is shown 95 curved, and it is so designed that it will continue to engage the stud 27 and force it down until the finger 15 is swung around into "cocked" position. Continued movement of the lever 30—29 in the same direction then causes the end of the lever 29 to pass over the stud 27, whereupon the trip lever will be snapped back by the springs 12 and 13 into the position shown in Fig. 2. As it is snapped it turns 100 the rotor or oscillator of the magneto 31 and generates an electromotive force and current in the ignition circuit including the generating coil of the machine 31, the wire 33, the fixed electrode 4, the movable electrode 3, the shaft 5, and the body of the igniter and bracket and connected parts, back to the generating winding, which is understood to be "grounded" on the frame. 105 At the proper instant when this electromotive force and current has reached its maximum, the inner end of the stud 27 strikes the screw tappet 26, and lifts the same so as to turn the dog 25 and the shaft 5, and thereby lift the movable contact 3 out of contact with the fixed electrode 4. The resultant spark fires the charge under compression and the engine starts. After starting in this way, the push rod 16 is reciprocated, and on the next stroke would engage the finger 15, but is lifted by the forward reciprocation of the exhaust valve operating rod 23, which throws the lever 21 to the left as shown in dotted lines and causes 110 the igniter to miss that stroke. At the 115 120 125 130

next stroke however, the push rod 23 being back, the push rod 16 advances and forces the finger 15 to the left (Fig. 2) until the trip lever 14 is in cocked position, when the 5 end of the push rod slips off the finger and the springs snap the trip lever back and produce a spark at the electrodes 3—4 in the same manner as before.

Referring now to Fig. 3, it will be observed that I have shown therein only the trip lever 14, the plate 6, and the hand firing lever 29^a—30^a. In this case the hand firing lever is carried on the stud or post *x*, attached to the cylinder or other portion of 15 the engine. The operation is the same as in the apparatus first described, except that the lever 29^a acts upon the finger 15 instead of upon the stud 27. Of course this must be so arranged that the lever will not offer any 20 obstruction to the push rod 16, but I have not deemed it necessary to indicate any special means for this purpose, as such means may be readily supplied by any one skilled in this art. The simplest manner of attaining 25 the desired end is to swing the lever 29^a—30^a into horizontal position when not in use, resting it against a stop *y*, the handle 30^a being made heavier in such case than the operating end 29^a.

30 I am quite well aware that a number of modifications may be made in non-essential features of this apparatus, and I wish it understood that I contemplate all such modifications as fall fairly within the scope of 35 the appended claims. For examples, the time eccentric or cam 17 may be mounted upon or combined with the lever 20, by being journaled upon a stud 20^a at the end of said lever; or the two lever arms 20 and 21 may 40 be formed separately with a tubular knuckle-joint between them, so that the angle which they form with each other may be varied, and the knuckle-joint would then be journaled upon the post 34, the two lever 45 arms 20 and 21 being rigid and moved together by the rod 23, but relatively adjustable for timing. I do not specifically claim all these modifications herein, but they fall 50 within the scope of the claims for my unit apparatus.

Having thus described my invention what I claim and desire to secure by Letters Patent is—

1. An ignition device for internal combustion engines comprising in combination 55 the following elements: an igniter body comprising a bracket and carrying a fixed electrode and a movable electrode with a shaft extending through the body, a trip lever adapted to actuate said shaft and electrode and to be actuated by an engine driven element, a magneto generator having a rotor adapted to be oscillated supported on the bracket and connected to said trip lever, and 60 a hand firing lever carried on a support in-

dependent of the magneto generator, and having a cam nose adapted when the lever is moved to engage the trip lever and in passing over the same to automatically release it at a predetermined point resulting 70 in an actuating movement thereof, to operate the magneto and the movable electrode shaft.

2. An ignition device for internal combustion engines comprising in combination 75 the following elements: an igniter body comprising a bracket and carrying a fixed electrode and a movable electrode with a shaft extending through the body, a trip lever adapted to actuate said shaft and electrode 80 and to be actuated by an engine driven element, a magneto generator having a rotor adapted to be oscillated supported on the bracket and connected to said trip lever, and a hand firing lever supported on said 85 bracket independently of the magneto generator, and having a cam nose adapted when the lever is moved to engage the trip lever and in passing over the same to automatically release it at a predetermined point resulting 90 in an actuating movement thereof, to operate the magneto and the movable electrode shaft.

3. An ignition device for internal combustion engines comprising in combination 95 the following elements: an igniter body comprising a bracket and carrying a fixed electrode and a movable electrode with a shaft extending through the body, a trip lever adapted to actuate said shaft and electrode 100 and to be actuated by an engine driven element, a magneto generator having a rotor adapted to be oscillated supported on the bracket and connected to said trip lever, and a hand firing lever supported on the 105 engine body independently of the magneto generator, and having a cam nose adapted when the lever is moved to engage the trip lever and in passing over the same to automatically release it at a predetermined point 110 resulting in an actuating movement thereof, to operate the magneto and the movable electrode shaft.

4. An ignition device for internal combustion engines comprising in combination 115 the following elements: an igniter body carrying a fixed electrode and a movable electrode with a shaft extending through the body, a frame attached to said igniter body, a bracket projecting from the frame, a trip 120 lever supported above the bracket, posts or studs on the frame with springs extending therefrom to the trip lever to actuate the same, an operating connection between said trip lever and the electrode shaft, and a 125 magneto having a rotor adapted to be oscillated mounted on the bracket and connected to the trip lever, all of said parts being arranged and mounted to form an integral self-contained unit, together with a 130

hand firing lever pivoted on a support independent of the magneto, and having a curved cam nose adapted when the hand lever is moved to engage the trip lever and force the same into cocked or firing position against the tension of the springs, continued movement of the hand lever thereafter releasing the trip lever having a cam nose and permitting it to actuate the magneto and movable electrode to fire the charge in the engine.

5. An ignition device for internal combustion engines comprising in combination the following elements: an igniter, a magneto and a trip lever for actuating the same, mounted and connected as a self-contained unit, with a hand firing lever pivoted independently of the magneto having a cam nose adapted when moved to actuate the igniter 15 and oscillate the magneto rotor.

6. An ignition device for internal combustion engines comprising in combination the following elements: an igniter body carrying a fixed electrode and a movable electrode with a shaft extending through the body, a trip lever supported by the igniter 20 25

assembly adapted to actuate said shaft and electrode and to be actuated by an engine driven element, and a hand firing lever having a cam nose adapted when the lever is moved to engage the trip lever and in passing over the same to automatically release it at a predetermined point resulting in an actuating movement thereof to operate the movable electrode shaft. 30 35

7. An ignition device for internal combustion engines comprising in combination the following elements: an igniter, and a trip lever with actuating parts therefor mounted and connected as a self-contained unit, and a hand firing lever supported by the igniter assembly having a cam nose adapted when moved to engage the trip lever and in passing over the same automatically release it at a predetermined point resulting in an ac- 40 45 tuating movement thereof.

In testimony whereof I hereunto affix my signature in the presence of two witnesses.
